UNITED STATES PATENT OFFICE.

LINNAEUS E. BAKER, OF FORT WAYNE, INDIANA, ASSIGNOR TO WAYNE COMPANY, OF FORT WAYNE, INDIANA, A CORPORATION OF INDIANA.

VISIBLE-LIQUID-DISPENSING APPARATUS.

Application filed April 25, 1924. Serial No. 708,912.

My invention relates to liquid dispensing apparatus of the so-called visible type, such as is commonly used in dispensing gasoline. The principal object of my invention is to make it impossible for the operator to so manipulate the apparatus as to cause it to deliver to the customer a less quantity of gasoline than that indicated as being sold. This is accomplished not only by exhibiting to the customer the quantity of gasoline he is to receive but also by exhibiting to him a flow indicator, so that he will know what becomes of the gasoline when he sees it is escaping from the visible container. So long as the "Serve car" sign is shown he will know the gasoline can flow only into the gasoline tank of his car, and so long as the "Drain-back" sign is shown he will know that the gasoline can flow only back into the storage tank. If the "Fill-bowl" sign is shown he will know that the gasoline can flow only into the visible container. When the flow indicator is set so as to exhibit any of these signs the appropriate valve may be opened, and so long as the position of the flow indicator is maintained the other valves are so guarded that they cannot be opened.

Some of the visible dispensing apparatuses now in use may be so manipulated as to simultaneously drain back gasoline from the visible container to the storage tank and deliver gasoline from the visible container to the car tank, thus cheating the customer. Some may be so manipulated as to simultaneously be filling the visible container and serving the customer, thus cheating the oil station proprietor. Other types of visible dispensers, whether interlocking or not, may have their valves manipulated in rapid succession and the customer cheated without his detecting the fraud.

My invention has a flow indicator operating in conjunction with a valve interlocking mechanism so as to prominently display to the customer the effect of the operator's manipulation of the valves.

Another object of my invention is to prevent a dishonest employee from cheating his filling station proprietor employer by simultaneously filling the visible container and serving the customer from a visible dispensing apparatus having a meter operated by the fall of liquid in the container and adapt-

ed to show the total quantity of liquid dispensed.

This invention, therefore, ensures fair treatment for both the pump owner and his customers, and meets the requirements of the United States Bureau of Standards and the Underwriters' Laboratories.

In the particular embodiment of my invention selected for illustration:

Fig. 1 is an elevation of so much of my improved visible gasoline dispensing apparatus as shows the valves controlling the flow of the gasoline into and out of the visible container; and the portions of the column and visible container adjacent thereto;

Fig. 2 is a cross section on the line 2—2 of Fig. 1;

Fig. 3 is a vertical section on the line 3—3 of Fig. 2;

Fig. 4, a detail, is a top plan view of the interlocking guard ring;

Fig. 5 is a section on the line 5—5 of Fig. 4;

Fig. 6 is a diagrammatic view of my invention as though the mechanism was arranged in a straight line instead of in ring form as shown in Fig. 2, shortened by breaking with the outwardly extending horizontal flange omitted; and

Fig. 7 is a vertical section on the line 7—7 of Fig. 6, shortened by breaking and with adjacent mechanism broken away.

Referring now to the drawings, 1 is the column portion of the dispensing apparatus, within which a pump or other mechanism may be housed; 2 is a cap of suitable design for the column, and 4 is an annular apron upon which is mounted the so-called "visible" container or glass. The apron 4 rests upon a container floor element 3^b, which is suitably supported on the column 1 by spool-shaped spacers 1^a. The cap 2 may, for convenience, be made in three sections held together by screws 2^a. A metal screen 3^a is provided to protect the container 3.

Gasoline is pumped to the container 3 through the pipe 5, controlled by the valve 6 which has lever 7. When the container 3 has been pumped full, excess gasoline is drained back to the storage tank through overflow pipe 8, which has no valve and is always open.

When gasoline is to be dispensed from the container 3 to a customer, the valve lever

11 is lifted, opening the serve-valve 10 allowing the gasoline to flow through the serve-pipe 9 to the hose (not shown).

When the apparatus is shut down at night, 5 any gasoline left in the container 3 must be drained back to the storage tank to minimize the fire hazard. To accomplish this the lever 14 of the drain-back valve 13 is raised, opening the drain-back pipe 12 and 10 allowing the gasoline to drain through the overflow pipe 8 back to the storage tank.

The fill valve lever 7 may be connected to any suitable valve or switch so as to simultaneously turn on power, forcing gasoline 15 from storage to the container 3 through the fill-pipe 5 and fill-valve 6 when said fill-valve is opened.

When the power used is compressed air 20 the connections may be as shown in Fig. 7, in which an air-valve 15, with suitable pipe connections, has its lever 16 connected by link 17 to an arm 18 on the fill-valve lever 7, so that when the operator desires to fill the container 3 and lifts the fill-valve lever 25 7 the air-valve 15 is simultaneously opened. By simply closing the fill-valve the air-valve is simultaneously closed so that the container may be filled to any desired level.

A guard-ring 19 is seated on the cap 2 30 under the apron 4 and may be partially rotated by means of the shift knob 20. In the apron 4 is cut a window 4^a through which a sign may be read. There may be as many 35 of these windows 4^a as are required to suitably advise purchasers of valve manipulations. Mounted upon the exterior wall of the upwardly extending rib 21 of the guard-ring 19 is a flow indicator plate 22 with signs adapted to be exposed to the view of 40 customers through the window. Only one of these signs can be seen at a time. Any suitable wording may be used on these signs, the ones shown being "Fill bowl" to indicate that the fill-valve is open and the container 3 being filled with gasoline; "Serve 45 car" to indicate that the serve-valve is open and gasoline flowing from the container 3 into the customer's car; and "Drain back" to indicate that the drain-back valve is open 50 and gasoline is flowing from the container 3 back into the storage tank. There will be a flow indicator plate for each window.

Detents 23, 24, 25, on the guard ring 19 are adapted to receive a spring pressed ball 35 26 to yieldingly hold the guard-ring in any of the setting positions. The guard-ring 19 has three keeper-notches 27, 28 and 29; 27 being adapted to receive the guard 7^a on the fill-valve lever 7; 28 being adapted to receive the guard 11^a on the serve-valve lever 11; and 29 being adapted to receive the guard 14^a on the drain-back lever 14.

When the guard 14^a of the drain-back lever 14 is in its keeper-notch 29, the drain-back pipe 12 is open so that gasoline will

flow to the overflow pipe 8 and the drain-back valve 13 may be locked in open position by the lock 30, the lock bolt entering the hole 32 in the boss 31. The guard-ring is then locked against rotation, making it 70 impossible to open either the serve-valve 10 or fill-valve 6 until the lock is unlocked.

When the guard-ring is in position so that any one of the valves may be opened the appropriate sign is exhibited in the window 75 4^a and no other valve can be opened until the ring is shifted and the appropriate sign for that other valve is displayed in said window.

Many changes may be made in this improvement from that herein shown and described without departing from the spirit of my invention; for instance, it may be adapted for use with any number of valves more than one and these valves may be variously grouped requiring shapes of guard element other than curvilinear. Without attempting to enumerate any substantial number of changes that might be made I claim as covered herewith any apparatus 80 readable upon the claims ultimately allowed hereon.

I claim as my invention and desire to secure by Letters Patent of the United States:—

1. In combination with a liquid dispensing apparatus having a container from which liquid is to be dispensed, a valve controlling the flow of liquid into said container, a valve controlling the flow of liquid from said container to the customer's container, and a valve controlling the flow of liquid from said container back to the storage tank; means for indicating which flow of liquid is to be established, and means for preventing the establishment of any other flow than the one indicated so long as that indication is maintained.

2. In combination with a liquid dispensing apparatus having an elevated container from which liquid is to be dispensed, a valve controlling the flow of liquid into said container, a valve controlling the flow of liquid from said container to the customer's container, and a valve controlling the flow of liquid from said container back to the storage tank; an adjustable flow indicator with a sign for each of said flow conditions, a window through which any one, but one only, of said signs may be seen upon adjustment of the flow indicator to any operating position, means for preventing the opening of any of said valves except that one which is in position when opened to permit the flow indicated by the designated sign through said window; and means for permitting the opening of the one of said valves which is in position when opened to permit the flow indicated by said sign.

3. In combination with a liquid dispens-

ing apparatus having an elevated container from which liquid is to be dispensed, a valve controlling the flow of liquid into said container, a valve controlling the flow of liquid from said container to the customer's container, and a valve controlling the flow of liquid from said container back to the storage tank; an adjustable guard element for said valves, a flow indicator on said guard element with a sign for each of said flow conditions, a window through which any one, but one only, of said signs may be seen upon adjustment of the flow indicator to any operating position, a guard fixed to each valve, a keeper-notch in said guard element for each of said guards on said valves, said combined guarding means being so arranged that only that valve can be opened which will produce the flow indicated by said exposed sign.

4. In combination with a liquid dispensing apparatus having an elevated container from which liquid is to be dispensed, a valve controlling the flow of liquid into said container, a valve controlling the flow of liquid from said container to the customer's container, and a valve controlling the flow of liquid from said container back to the storage tank; an adjustable guard element for said valves, a flow indicator on said guard element with a sign for each of said flow conditions, means for designating which one of said signs is controlling upon adjustment of the flow indicator, a guard fixed to each valve, a keeper-notch in said guard element for each of said guards on said valves, said combined guarding means being so arranged that only that valve can be opened which will produce the flow indicated by said designated sign.

5. In combination with a liquid dispensing apparatus having a container from which liquid is dispensed, means for controlling the flow of liquid into said container,

means for controlling the flow of liquid from said container to the customer's container, means for controlling the flow of liquid from said container back to storage, an adjustable guard element for said flow control means, a flow indicator on said guard element with a sign for each of said flow conditions, means for determining which one of said signs is controlling upon adjustment of the flow indicator, a guard and a keeper for each of said flow control means and its coacting part of said guard element, said combined guarding means being so arranged that only that flow controlling means can be opened which will produce the flow indicated by said designated sign.

6. In combination with a liquid dispensing apparatus having a container from which liquid is dispensed, a conduit through which liquid is supplied to said container, a conduit through which liquid flows from said container to the customer's car, a conduit through which liquid drains from said container back to storage, a valve in each of said conduits controlling the flow of liquid therethrough, a fixed overflow pipe through which excess liquid supplied to said container automatically drains, an adjustable guard element for said valves, a flow indicator on said guard element with a sign for each of said flow conditions, means for determining which one of said signs is controlling upon adjustment of the flow indicator, a guard fixed to each of said valves and a co-acting keeper notch in the adjustable guard element for receiving each of said guards, said combined guarding means being so arranged that only that valve can be opened which will produce the flow indicated by said designated sign.

In testimony whereof I have hereunto set my hand.

LINNAEUS E. BAKER.
